Primary Examiner—Carol Rademaker*(74) Attorney, Agent, or Firm*—Michael J. Kline(57) **CLAIM**

We claim the ornamental design for a bottle, as shown and described.

DESCRIPTION

FIG. 1 is a front right perspective view of a bottle showing our new design;

FIG. 2 is a left side elevational view thereof;

FIG. 3 is front elevational view thereof;

FIG. 4 is right side front elevational view thereof;

FIG. 5 is back elevational view thereof, the left side elevational view being identical;

FIG. 6 is a top plan view thereof; and,

FIG. 7 is a bottom plan view thereof.

The broken lines in the drawings are for illustrative purposes only and form no part of the claimed design.
